ELECTRIC CIRCUITS FOR LAMP
REGULATIONWillard C. Hall, Jr., Los Angeles, Calif., assignor
to Lloyd O. James, Los Angeles, Calif.

Application August 7, 1939, Serial No. 288,781

2 Claims. (Cl. 176—124)

This invention relates to means and methods for regulating and controlling electrical devices and the power factor of the circuit connected thereto. Although the invention has many uses and adaptations when connected with different kinds and types of electrical equipment such as motors, plating baths, instruments, rectifiers, converters, etc., its principal demand and advantages is in the regulation and control of lighting devices, particularly for luminous electric discharge tubes which utilize various gases for conduction of electrical energy through the tubes.

Such tubes are commonly known as "neon tubes" even though the rare neon gas, which provides the familiar red light, is not present in the tube. Other gases such as argon, helium, carbon dioxide, sodium vapor, mercury vapor, etc. and mixtures thereof are also used to provide other light colors and various shades thereof. There are many kinds and types of low and high pressure vapor tubes which consist of various kinds of glass, colored and clear, to withstand the heat evolved and also mechanical shocks encountered in ordinary use. Some of them are coated with a luminescent material to give the effect desired. This invention, however, is not limited to any specific type of illuminating unit or units, but can be altered and arranged to be effective to improve the operation of any such unit or units whether connected in single units or banks of parallel or/and series units.

The gas pressure in the tube is of importance since this determines the striking potential and operating voltages to be supplied thereto. The electrical characteristics of the electrodes also have some bearing in the matter, but since they can be accurately predetermined and perfectly designed for any particular lamp, they will not be further considered. The major features for consideration in heated cathode tubes are the gas pressure (or pressures where mixtures of gases are employed) and the fact that when the starting voltage drops the current increases. In view of the fact that a relatively high striking voltage must be initially provided, automatic means must be provided to reduce the striking voltage to a minimum operating value in order to maintain the current in the circuit at a reasonable value.

This invention keeps the current constant, provides a leading current at the striking voltage and a power factor of 90% or better during the normal operation of the vapor tube. This is accomplished by connecting in the circuit a condenser having a reactance greater than the in-

ductive reactance at the time the tube is under the influence of the striking voltage, but when the tube is at normal operation, the voltage drops from its relatively high value with a proportionate drop across the condenser with the result that the current lags the voltage but not sufficient to lower the power factor to less than 90%. Such a circuit is favored by the power supply companies over present vapor tube circuits. Heretofore, so far as known, no means have been provided to automatically improve the power factor of vapor tube circuits in a safe and simple manner. Such tubes normally operate at a 50%, or less, power factor.

The vapor tube circuit embraced by this invention uses no switching mechanism nor thermoelectric devices to accomplish the desired power factor results or the improved efficiency of vapor tube circuits. The life of the tubes, operated in accordance with this invention, are materially increased because the cathodes thereof are kept at a high efficient heat at all times; this avoids sputtering at the cathodes, and loss of efficiency because of distortion of the desirable sinusoidal voltage and current wave forms. Therefore, the current in the tube is kept constant, the illumination always at its maximum, and hence its effectiveness 100% from an attractive aspect.

In the cold electrode type of tube, conditions of operation, as regards voltage and current, are quite different. In this type of tube, current passes by virtue of ionisation by collision of the gas atoms and produces either a negative or positive glow depending upon the gas pressure and the disposition of the electrodes thereof.

This invention, however, is equally applicable to the so-called cold electrode lamps as set forth, merely as an example, in one specific form of applying the invention. Since there are a great variety of illuminating lamps, no attempt is made to apply the invention to every kind of lamp or other electrical device.

An object of the invention is to provide means and methods for starting and continuously operating electrical devices at a high power factor, and a dependable constant current.

Another object is to present an electrical circuit without mechanical moving parts capable of starting and continuously operating luminous vapor tubes at a power factor of 90% or better.

Still another object is to provide means for operating one or more units of high or low pressure gas filled illuminating tubes at a very high efficiency.

Other objects, advantages and features of my

invention will appear from the accompanying drawings, the subjoined detailed description, the preamble of these specifications and the appended claims.

Applicant is about to illustrate and describe various forms of his invention in order to teach one how to make, use and vend the same, but it is to be understood that the drawings and description thereof are not to limit the invention in any sense whatsoever, except as limited by the appended claims.

In the drawings:

Fig. 1 shows one form of the invention in plan view.

Fig. 2 shows the same inventive form diagrammatically.

Fig. 3 shows a detailed portion of an electric discharge tube.

Fig. 4 shows a slightly modified form of the invention diagrammatically.

Fig. 5 illustrates diagrammatically another form of the invention.

Fig. 6 is a plan view illustrating the manner in which the coils shown in Fig. 5 are preferably mounted upon the same magnetic core.

Figs. 7 and 8 are another form of the invention shown in plan view and diagrammatically respectively.

In the preferred form of the invention, as shown in Figs. 1, 2 and 3, the numeral 1 represents an elongated vapor tube having the heated electrodes 2 and 3 at the ends thereof. This tube may be of glass containing a mixture of argon gas and mercury vapor at a relatively low vapor pressure. Since the construction and operation of these tubes are well known, no special details thereof will be given.

The numeral 4 represents a laminated core in the form of a rectangle having a closed metallic path for the flux thereof. The core has a laminated midway bridge 5 which has its ends slightly spaced from the core by fiber spacers 6 and 7 which are wedged between the ends of the bridge and the inner sides of the core as shown. Mounted upon the core to one side of the bridge is the single coil 8 and a transformer coil 9, the primary being indicated by the reference character 10, and the secondary by the reference character 11. Mounted upon the core on the opposite side of the bridge 5 is a single coil 12, and the auto-transformer coil 13.

From the auto-transformer coil 13, at the proper voltage tap, lead the wires 14 and 15 which are connected to the opposite ends of the heating element 3 of the tube. From the secondary coil 11, lead the wires 16 and 17, the wire 16 connecting with one side of the heating element 2 and the wire 17 connecting with the other side of said heating element, the wire 17 also acting as one of the supply mains and is extended by the wire 18 for connection with the city mains of 120 volt, 60 cycle alternating current. Another supply main 19 leads to the primary winding 10, best shown in Fig. 2, from the opposite end of which leads a wire 20 connecting with one end of the coil 8. From the opposite end of the winding of coil 8 leads a wire 21 making connection with one end of the coil 12, the other end of this coil winding is connected to a wire 22 which makes connection with one end of the auto-transformer coil 13. A wire 23, connected to the wire 21, leads to a set of plates in the condenser 24. From the opposite set of the condenser plates leads a wire 25 which makes connection with the wire 16 as shown.

The coil sets on either side of the bridge 5 of the core have equal inductances and are wound to create opposing flux in the iron core; the paths taken by the flux would be as indicated by the arrows. This bridge is very effective in holding the tube current constant and also reduces heating by providing a good path for the opposing flux.

For operating a single 20 watt vapor tube, 24 inches long and a diameter of 38 mm., containing argon and mercury at a vapor pressure of about 2 mm. of mercury, connected to supply mains giving 120 volts at 60 cycles, the coils upon the iron core 4 are preferably arranged as shown in Fig. 1. The coil sets on either side of the bridge 5 is wound with #25 B. & S. gauge copper wire, the combined number of turns for each set being about 1980. Since the cathodes 2 and 3 are designed to operate at a potential of 6.2 volts, a tap at about 80 turns is made on the auto-transformer 13 for heating the element 3 and a secondary winding of 80 turns is utilized in the coil 11 for the heating of the element 2. At these values, the condenser 24 should have a capacity of about 3 microfarads. Under these conditions, the tube will have a starting voltage of about 220 and an operating voltage of 65. At starting, the drop across the condenser should be 230 volts and under normal operation of the tube about 90 volts. This drop across the condenser shifts the power factor from a leading value to about 90% or better at a lagging position. The current remains constant at 0.3 ampere under starting and operating conditions. The power factor reading at operating potential is close to 92% where as the starting potential definitely gives a leading power factor reading.

In the form of the invention shown in Fig. 4, the vapor tube is indicated by the numeral 26 which has the usual heated electrodes at its ends; from one of which leads the wires 27, 28 and from the other wires 29 and 30. The induction coil pairs are indicated by 31 and 32, one end of the coil 32 acting as an auto-transformer to feed one of the electrodes as indicated by the connection of wires 29 and 30, and the other induction coil 31 has its end connected to the supply main 33. One end of the coil 31 is shown as having a secondary winding 34 which supplies current by the way of wires 27 and 28 to the other electrode of the tube.

The supply main 35 is connected to the electrode feeder wire 28 as shown. As explained in the preferred form of the invention, the induction coils 31 and 32 are wound oppositely upon the core to cause opposing flux at the ends of the bridge so that it functions as a regulator. In the jointure of the coils 31 and 32 leads a wire 36 which connects to one end of a choke coil 37. From the other end of the choke coil leads a wire 38 connecting with the condenser 39, the other side of the condenser having a wire 40 connecting with the electrode feeder wire 27.

The only change in this circuit over the one shown in Fig. 2 is the addition of the choke coil 37 in the condenser line and also the condenser 39 across the main feeders. This coil functions to avoid serious kickback voltages from the condenser and hence possible resulting fluctuations in the illumination of the tube.

The circuit including the condenser 39, choke coil 37 and inductance coil 31 is designed for a resonance balance during the normal operation of the tube 26 while its voltage is at a minimum,

the power factor at 90% and the frequency 60 cycles.

In the form of the invention shown in Figs. 5 and 6, two vapor tubes are operated by a common circuit arrangement. The electric discharge 5 tubes are indicated by the numerals 41 and 42. The induction coil bank of this form of the invention consists of a plurality of coils 43 and 44 which are wound in opposite directions causing opposing flux in the laminated iron core 45; 10 similar coils 46 and 47 are mounted on another leg of the core. A magnetic bridge 48 provides the shunt to avoid flux flow interference as set forth in the foregoing forms of the invention.

The end coils 43 and 47 have secondary windings 49 and 50 for feeding the electrodes 51 and 52 respectively at the ends of tube 42 as shown. The primaries of coils 43 and 47 are tapped at 15 53 and 54 to provide auto-transformers for feeding the electrodes 55 and 56 respectively of the tube 41. Although the auto-transformer taps are shown as embracing the same number of turns as the secondaries, this need not necessarily be the case since the electrodes of tube 41 may require a higher voltage than tube 42 because of 20 their lengths or their difference in design. The wires connecting the coils with their respective electrodes are shown as the primes and double primes of their respective electrodes.

Wire connectors are shown between the various 30 coils, the center connector 57 being joined to the supply main 58 of an alternating current source; the frequency and voltage of which will depend upon the available supply, but since a 60 cycle 120 volt supply is common in this country, such a source is preferred. The other main 59 leads via wires 60 and 61 to the middle tap of the secondary coils 49 and 50 respectively and to a side of the condenser 62 by a wire 63. The other side of the condenser is joined to a wire 64 which makes connection at the point 65 with the connector between the coils 46 and 47.

This form of the invention like the other forms shown in Figs. 1 to 4, has all the same advantages and operating characteristics.

The form of the invention shown in Figs. 7 and 8, appertain to the so-called "cold electrode" type of electrical discharge tube which starts operation by virtue of atomic bombardment to effect ionisation of the gas. The resulting glow may be due to either a positive or negative column depending upon the arrangement of the electrodes and the pressure of the confined gas or gases.

In the drawings, the reference character 65 55 indicates one of the so-called "cold electrode" tubes; it being understood, however, that a plurality of such tubes may be connected in series, parallel or series-parallel arrangement, and the invention would be just as effective in giving the desired results.

At one end of the tube 65, is an electrode 66 and at the other end, electrode 67. These electrodes are in the form of a coiled wire, the ends of which have leads which terminate into a single exterior wire; one such wire is indicated by 68 for the electrode 66 and another wire 69 for the electrode 67. Wire 69 is a main as well as the wire 71 leading to the coil 70' and they are connected to a source of current of suitable voltage 70 and frequency.

The coil 70' and its component coil 70" comprise a coil 70 having its windings arranged to cause flux to flow in the core 72 in the direction shown by the arrows. Another composite coil 73

having component parts 73' and 73" are fixed on the core 72, as shown, and are wound to cause flux to flow in the direction as indicated by the arrows. The core 72 is also provided with the magnetic bridge 74 spaced from the iron of the core 72 by fibre wedges or the like. This bridge 74 enhances the automatic control of the voltage and current through the tube and also avoids core heat.

One end of the winding of coil 73' is connected to wire 68 and the other end to coil 73". Coils 70' and 70" are connected in series also. The other ends of the coils 70" and 73" are connected by a wire 75 from which leads a wire 76 to one side of the condenser 77. A choke coil 78 is inserted between the other side of the condenser and the main 69. A condenser 79 is provided across the mains.

In the circuit just described, the tube may contain sodium and mercury vapors at a pressure of between 8 and 15 mm. of mercury. The voltage across the mains should be 230 and the frequency 60 cycles. This type of high pressure tube would require a starting line voltage of 230 at 1.8 amps., and an operating line voltage of 230 at 3 amps. to maintain the lamp at maximum illumination of about 440 watts input. The lamp running voltage itself while cold is 65 which rises almost to line voltage when at full illumination. The power factor rises as the tube voltage increases because the drop across the condenser also rises to cause a beneficial increase in capacitive reactance.

During the starting period of the tube, the circuit comprising the coils 70', 70", 78, and the condenser 77, is near resonance while the input power is near 90% power factor. As the temperature of the tube rises, there is a greater voltage drop across it and also across the element 70', 70", 77 and 78, thus increasing the inphase flux in coils 70' and 70" with respect to coils 73' and 73" on the same magnetic core; this increases the impedance of the regulator coils. At start, the tube has an input of 200 watts which rises to 440 watts at full illumination.

Such tubes in the ordinary circuits take 20 minutes to come to full illumination from a cold start whereas with this invention applied, the same tube requires only 15 minutes. Should a break in the current supply occur, the tube with the ordinary circuit would require 10 minutes to re-ignite and a few minutes more to come back to full illumination whereas when this invention circuit is employed, the tube ignites immediately and regains full illumination shortly thereafter. The reason for this advantage in applicant's circuit appears to be that the condenser and inductance coils immediately increase the voltage across the tube to substantially twice that of the line voltage. The circuit is kept near resonance at all times, hence a high power factor is maintained.

At start, on a constant potential line voltage of 220 A. C., a similar lighting tube to the one just explained would draw 0.9 of an ampere or 185 watts at a volt-ampere reading of 198, thus working at a power factor of 93%. Five minutes later, the watt meter would read 240 and the volt-amperes 242 giving a power factor of 95%. Ten minutes later the reading would be 265 watts and 275 va. or 96% P. F.; fifteen minutes later 300 w. and 304 va. or 98% P. F.; twenty minutes later 320 w. and 330 va. or 97% P. F. In twenty-five minutes, the tube would be at full luminosity and the line reading 400 w. and 418 va., and have

a P. F. of 95%. These figures are given from an actual test and show that applicant has presented a circuit which successfully operates a gas filled electrical tube at a high power factor from start to full operating condition.

Having thus described my invention, what is claimed as new and desired to be secured by Letters Patent is:

1. In an electrical circuit for regulating a plurality of lighting devices at a high power factor; a magnetic core having long legs joined together by short legs at the ends thereof, a magnetic bridge of large cross section wedged between the long legs at the longitudinal centers thereof, a plurality of induction coils arranged in series and fixed to the core on the long legs, said coils being positioned on both sides of the bridge and arranged to cause the flux generated in the coils of each leg to flow in opposition and then pass across the bridge in a common direction, a supply of electrical current for energizing said coils and devices, a condenser connected between one lead of the electrical supply and a point between the coils on one leg of the core.

2. An electrical system for starting and maintaining gaseous electric discharge lamps at a high power factor including a magnetic core having two coil legs joined at their ends by means to form an iron circuit, a pair of spaced apart coils wound in opposite directions on each coil leg, a magnetic bridge across the spaces between said coils, said coils having a series connection and a wire terminal at each end of the series and also at the mid-point of the series, an electric discharge lamp having a terminal at each end, one terminal of the lamp having connection with one end of the series of coils and the other end terminal of the lamp having connection with wire means leading to a source of electrical power, the other end terminal of the coils having connection with said power source, and a choke coil and condenser connected in series and having one end thereof connected to said wire means and the other end thereof connected to the mid-point of the coils.

WILLARD C. HALL, JR.
